UNITED STATES PATENT OFFICE.

GUSTAV EGLOFF, OF CHICAGO, ILLINOIS.

PROCESS OF TREATING HYDROCARBONS.

Application filed July 19, 1918, Serial No. 245,592 Renewed April 21, 1928.

This invention relates to improvements in process of treating hydrocarbons and refers more particularly to the treatment of high boiling point oils such as petroleum residues, spruce turpentine, high boiling coal tar oils and the like, to convert the same into lower boiling point oils.

Among the objects of the invention are to dissociate the oil by means of an efficient introduction into the oil of aluminum chloride and in such a way as to insure the aluminum chloride thoroughly mixing with the oil.

By the use of aluminum chloride as a dissociating reagent the temperature of the oil may be kept below the normal distilling point of the highest boiling point constituents of the oil being treated. For example, in some instances, if the oil boils at 750° F. it may be dissociated at a temperature of about 300° F. The variation of temperature, of course, depends very largely upon the character of oil being treated.

In the present invention, aluminum chloride may be used as such or generated in the body of the oil in the still by putting into the latter aluminum in the form of shavings, sheets or powder and then adding corrosive sublimate or some other sub-catalyst and then passing hydrogen chloride gas or chlorine gas through the body of the oil and the solid substances in the still. Preferably, before the gases are passed through the oil the solid substances and the oil in the still are heated. The aluminum chloride forming reaction takes place more efficiently if the oil is heated before the gases are passed through it.

In the accompanying drawing the figure there shown illustrates an apparatus in which the invention may be carried out. In the drawing, 1 designates a vertical still mounted in a furnace 2. A reflux condenser 3 which may take the form of a conduit, in which is interposed a valve 4, leads from the top of the still to a water cooled condenser coil 5, which in turn is connected to a receiving tank 6. This tank 6 is provided with sight gauge 7, pressure gauge 8, draw-off pipe 9, the last being provided with throttle valve 10. The oil and aluminum chloride are circulated by means of circulating pump 11, pipe 12, and spray 13. The rate of circulation is controlled by means of valve 14. A pipe 15 leads from the end of the still 1 to the circulating pump and valve 16 is interposed as

safety. The dotted line 18 indicates the level of the oil and the dotted line 18' the level of the aluminum chloride. The rose 19 is attached to a source of chloride forming gas and controlled by valve 20. The oil is introduced by the pump which is connected to any suitable source of supply (not shown). The catalyst is introduced through suitable manholes (not shown) and the subcatalyst in the same way. The excess chlorine and other fixed gases pass out through the gas outlet 6' controlled by the valve 7'. The carbon is removed by manhole plate (not shown).

In order to more clearly practice the invention, I give herewith an illustrative run:

The method which I have found to be advantageous is to charge the still with hydrocarbon oil adding to same 1 to 2 percent aluminum powder by weight of the oil plus one-tenth of one percent "corrosive sublimate" by weight of the oil. The oil is heated, and while heating same hydrogen chloride gas is passed through the rose (19) shown in the drawing which gas in the presence of "corrosive sublimate" reacts immediately with the aluminum forming aluminum chloride. Without the "corrosive sublimate" present the formation of the aluminum chloride is very slow in hydrocarbon liquid. The action of the "corrosive sublimate" is to act catalytically with aluminum chloride in the presence of hydrocarbon liquid and also to assist in the catalysis of the said hydrocarbon liquid and I have called this "corrosive sublimate" a sub-catalyst and the aluminum chloride the catalyst in the reaction of forming low boiling hydrocarbons from high boiling hydrocarbons. The temperature of the body of oil and aluminum chloride is maintained at 450° to 500° F. and the temperature of the vapors leaving the still is maintained at 400° F. so as to produce a present marketable gasoline having an approximate end point distillation of 440° F.

The pressure on the system is atmospheric, although at times a pressure of two to five pounds has developed on still, due to the friction of the pipes and some volatilized aluminum chloride passing out of the system and recondensing in the piping system. The rate of distillation of the hydrocarbon liquid was 3 to 5 percent of the still charge per hour. The percentage yield of marketable gasoline obtained using kerosene of 42 Baume gravity

ranged between 23 to 30 percent and was found to be dependent upon the velocity of spraying hydrocarbon liquid and aluminum chloride liquid into the still; also the temperature in the oil and the concentration of aluminum chloride.

The main function of the "corrosive sublimate" is to act catalytically with aluminum chloride by the use of hydrogen chloride or chlorine with aluminum in the presence of hydrocarbon liquid.

The "corrosive sublimate" also acts as a catalyst in forming light gravity hydrocarbon liquid from heavy gravity hydrocarbon liquid but only slightly in comparison to the aluminum chloride, hence, in this process the aluminum chloride is the normal catalyst and "corrosive sublimate" the "sub-catalyst."

I have found that by circulating from the still, oil and aluminum chloride through a spray nozzle into the still again, that the speed of conversion of the heavy hydrocarbon oil into light oil is much greater than by simply heating the aluminum chloride in the presence of the oil or by use of a mechanical stirrer. An enormously greater contact surface of the aluminum chloride is attained by circulating and passing through a spray device. The usual method of conversion of hydrocarbon material by aluminum chloride treatment, is by means of heat, or heat and a mechanical stirrer set in the body of the oil. From my observation of the aluminum chloride reaction upon hydrocarbon oil, as the reaction proceeds, the aluminum chloride layer develops a deep red color, which after a time permeates the body of the oil when starting with oils as kerosene, gas oil or lighter colored oils. The reaction area by the ordinary aluminum chloride treatment of hydrocarbon oils, is solely between liquid surfaces, whereas my improvement in the art gives enormously larger reaction areas in unit time,

due to circulating and spraying the liquids into the still, in a state of fine division.

I have found that my process increases the amount of product formed in a given time over the older method devised for the aluminum chloride treatment of hydrocarbon oils.

I claim as my invention:

1. A process of treating hydrocarbon oil comprising heating said oil maintained in a substantial liquid body in the presence of aluminum chloride, maintaining a temperature within said body above the melting point of the aluminum chloride and sufficient to vaporize portions of the oil, withdrawing the unvaporized oil and aluminum chloride from the lower part of the liquid body and reintroducing same to the upper part of the liquid body, and continuing such circulation during the treatment, the oil and chloride being returned to the liquid body in an atomized condition.

2. A process of converting hydrocarbon oil into lower boiling point products consisting in heating the oil in a receptacle in the presence of aluminum chloride, the temperature being raised above the melting point of aluminum chloride, and sufficient to vaporize part of the oil, removing the vapors, withdrawing the unvaporized portions and passing them, under pressure, to a zone where they are permitted to expand, in atomized form, and re-treating such unvaporized portion.

3. A process of converting hydrocarbon oil into lower boiling point products consisting in heating the oil in a receptacle in the presence of aluminum chloride, the temperature being raised above the melting point of aluminum chloride, and sufficient to vaporize part of the oil, removing the vapors, withdrawing the unvaporized portions and passing them under pressure to a zone where they are permitted to expand in atomized form.

GUSTAV EGLOFF.
